(57) **CLAIM**

The ornamental design for a cable lock, as shown and described.

DESCRIPTION

The patent or patent application file contains at least one drawing executed in color. Copies of this patent or patent application publication with color drawing(s) will be provided the Office upon request and payment of the necessary fee.

FIG. 1 is a top plan view of a cable lock showing my new design;

FIG. 2 is a top, front and left perspective view thereof;

FIG. 3 is a top, rear and left side perspective view thereof;

FIG. 4 is a top plan view thereof, shown in open position;

FIG. 5 is a top, front and left perspective view, shown in an open position;

FIG. 6 is a top, rear and left side perspective view, shown in an open position;

FIG. 7 is a bottom plan view thereof;

FIG. 8 is a bottom plan view, shown in an open position;

FIG. 9 is a front elevational view thereof;

FIG. 10 is a left side elevational view thereof;

FIG. 11 is a rear elevational view thereof; and,

FIG. 12 is another left side elevational view, shown in upside down position.

The cable showing as environment and forms no part of the claimed design.
